US0D1072721S

(12) **United States Design Patent** (10) Patent No.: **US D1,072,721 S**
(45) Date of Patent: ** Apr. 29, 2025

(54) **ONE-WAY CHECK VALVE**

(71) Applicant: **Improved Racing Products, LLC**, Orlando, FL (US)

(72) Inventors: **Richard Michael Ihns**, Orlando, FL (US); **Casey A. Fitzgerald**, Orlando, FL (US); **Jarott E. Nelson**, Orlando, FL (US)

(73) Assignee: **Improved Racing Products, LLC**, Orlando, FL (US)

(**) Term: **15 Years**

(21) Appl. No.: **29/896,025**

(22) Filed: **Jun. 28, 2023**

(51) LOC (15) Cl. **12-15**

(52) U.S. Cl. USPC **D12/606**

(57) **CLAIM**

The ornamental design for one-way check valve, as shown and described.

DESCRIPTION

FIG. 1 is a first perspective view of a one-way check valve employing an ornamental design in accordance with the present invention;

FIG. 2 is a second perspective view thereof;

FIG. 3 illustrates a first side view thereof;

FIG. 4 illustrates a second side view thereof;

FIG. 5 illustrates a front view thereof;

FIG. 6 illustrates a rear view thereof;

FIG. 7 illustrates a third side view thereof; and,

FIG. 8 illustrates a fourth view of thereof.

The broken line portions of FIGS. 1-8 are included to show unclaimed subject matter only and form no part of the claimed one-way check valve.

1 Claim, 8 Drawing Sheets
